No. 234.

John M. French assignee of Calum Fulton
Design for Stores - Patented Sept. 25 1849

Ms. 234

John M. French, Atte of Calvin Fulton, Rochester, N. Y.
Letters Patent No. 234. Dated September 25, 1849.

The schedule referred to in these Letters Patent and making part of the same.

To all whom it may concern:

Be it known that Calvin Fulton, of the City of Rochester, County of Monroe and State of New York, have invented or produced a new ornamental design for a stove plate, and I do hereby declare that the following is a full and exact description of the same, reference being had to the annexed drawings, making a part of this specification — in which Fig. 1 is an elevation of my ornamental design for a stove plate, Fig. 2 is a section through
ornamental moulding at E, Fig. 1.

What I claim as my invention and desire to secure by letters patent is the ornamental design of a stove plate, substantially as herein described and represented.

Witnessed
W. L. Burris
J. H. Shelmire.
